Int. Cl. D6—04

U.S. Cl. D6—190

FIG. 2.

FIG. 3.

FIG. 1 is a front perspective view of a merchandise display and storage unit embodying my new design;

FIG. 2 is a top plan view thereof; and

FIG. 3 is a front elevational view thereof. The broken line representation of displayed merchandise in FIG. 1 is for purposes of illustration only. It is to be understood that the left-most panels in FIGS. 1 and 3 are shaded to show contrast of materials.

I claim:

The ornamental design for a merchandise display and storage unit, substantially as shown and described.
